APPARATUS FOR PRODUCING SURFACES
OF REVOLUTION ECCENTRIC TO ONE
ANOTHER

Albert H. Dall, Cincinnati, Ohio, assignor to Cincinnati Grinders Incorporated, Cincinnati, Ohio, a corporation of Ohio

Application July 28, 1933, Serial No. 682,662

9 Claims. (Cl. 51—105)

This invention relates to improvements in machine tool structures, particularly grinding machines, and to an improved method for producing arcuate surfaces eccentric to one another.

5 One of the principal objects of the present invention is therefore the provision of an improved method and improved apparatus for producing a surface of revolution eccentric to a preformed surface of revolution.

10 Another object of the invention is the provision of an improved method and apparatus for grinding an exterior surface of revolution about a center laterally spaced with respect to the center of a previously formed internal surface of revolution.

15 A further and specific object of the invention is the provision of an improved method and apparatus for grinding the arcuate contact face of the lug on rocking shoe journal bearings in definite predetermined relation to the arcuate bearing face of the said segmental rocking bearing shoes.

20 Other objects and advantages of the present invention should be readily apparent by reference to the following specification, considered in conjunction with the accompanying drawings forming a part thereof and it is to be understood that any modifications may be made in the exact structural details there shown and described, 25 within the scope of the appended claims, without departing from or exceeding the spirit of the invention.

In the drawings:

25 Figure 1 is a front elevation of a grinding machine for carrying forward the improved method and showing the improved apparatus in place.

Figure 2 is a sectional view taken on the line 2—2 of Figure 1.

30 Figure 3 is a sectional view taken on line 3—3 of Figure 2.

Figure 4 is an elevational view of a portion of the work supporting mandrel as seen from line 4—4 on Figure 3.

35 Figure 5 is a perspective view of a segmental rocking bearing shoe, illustrating one type of work adapted to be finished by improved method and apparatus of this invention.

40 Throughout the several views of the drawings similar reference characters are employed to denote the same or similar parts.

45 As was noted above, this invention pertains to an improved method and apparatus for producing arcuate surfaces of revolution eccentric to a previously formed surface. One type of work adapted to be finished by this improved method and

5 apparatus is the rocking bearing shoe shown in Figure 5, and it is deemed expedient if a description thereof be given in order to more fully understand the invention. The rocker bearing shoe 10, therefore, comprises an arcuate bearing face 11 which is formed to a radius substantially equal to that of the spindle or shaft journal with which it is to be used. The shoe 10 is of a length substantially equal to the length of the journal which it is adapted to support. On the back face 12 of 10 the shoe it is provided with a lug 13 having its outer surface arcuately shaped or rounded as indicated at 14. The rounded portion 14 is generated about an axis that is spaced from the axis of the bearing face 11. 15

10 The shoes when placed in use are disposed within a bore in the spindle or shaft housing, which bore is formed substantially concentric with the bearing face 11 from which it follows that the radius at the surface 14 is different from 20 the radius of the bore. As a matter of fact, the radius of the arcuate or bearing surface 14 is less than the radius of the bore in which the shoes are disposed, but this radius is greater than the radius of the contact or bearing face 11. In 25 order to finish the surface 14 it is desirable to rotate the shoe 10 about an axis while adjacent to a tool or grinding wheel. At the same time the shoes cannot be rotated about the axis of the bearing face 11 since this would produce the surface 30 14 as concentric with the said face 11.

35 Resort was therefore had to a supporting mandrel 15 to which is secured a plurality of the shoes which are simultaneously operated upon. This mandrel 15 was provided adjacent each end 35 with a plurality of circumferentially spaced pins 16 and 17 which pins are individually in alignment with one another to provide spaces or portions 18', 19', 20', 21', 22' and 23' between them, each of which supporting portions is 40 adapted to receive a work piece or segmental shoe 10. Each supporting portion of the mandrel is formed about its own axis or center, such as 18, 19, 20, 21, 22 and 23 and of a radius equal to the radius of the bearing face 11 of the work. 45 It is to be understood that the supporting portion 18' is formed about the axis or center 18, supporting portion 19' about the axis or center 19, etc. By this construction the normal axis 24, or the axis of the mass of the mandrel, became 50 the axis about which the arcuate contact face 14 was to be formed and this axis 24 is equally spaced from each of the other axes 18 to 23 inclusive. By reference to Figure 2, it will be noted that the axis 24 and each of the other axes 55

are respectively in line with the center of the work supporting portion between adjacent pins 16 and 17. It will also be noted that the mandrel 15 is provided with a plurality of arcuate seats, each being disposed between adjacent pins 16 and 17 and each adapted to receive a work piece.

In order to hold the shoes on the mandrel during the operation on the lugs 13 for the formation of the contact surfaces 14 there is provided 10 a pair of rings 25 and 26, which encircle the mandrel and work on opposite ends of the lugs 13. The rings 25 and 26 respectively carry work clamping screws 27 and 28, there being as many clamping screws as there are work pieces finished 15 at one setting, here shown as 6 in number. Therefore, after the work pieces have been mounted on their respective mandrel supporting seats, the rings are placed over the work and mandrel and the clamping screws drawn home. 20 The entire assembly is then placed in a machine tool and rotated about the axis 24 and a tool brought into position for engagement with the ribs 13 of the work.

Figure 1 shows a center type grinding machine 25 with the mandrel and the work mounted in position thereon. As there shown, the mandrel is supported by centers 29 and 30 respectively carried by the headstock 31 and tailstock 32. The said head and tailstocks are in turn secured to a work supporting table 33 mounted on suitable 30 guide ways provided by a bed or support 34.

The bed 34 supports the usual grinding wheel slide 35 having bearings 36 formed thereon in which is disposed a spindle for the grinding wheel 37. In addition, the carriage 35 has secured to it a guard or housing 38 which substantially encircles the grinding wheel 37 for confining the coolant usual with grinding machines. Any suitable means may be provided for effecting the 40 rotation of the spindle and grinding wheel at the usual high grinding rate of speed.

In order to rotate the work while supported on the centers 29 and 30 the headstock has associated therewith a face plate 39 from which projects 45 the driving pin 40 that contacts with the work driving dog 41 secured to the reduced extension 42 of the mandrel 15.

The tool slide 35 is adapted to be actuated laterally of the bed 34 toward the work table 33 50 and any suitable means may be provided for this purpose. As shown in the drawings, this means may comprise the usual cross feed mechanism which terminates in the hand wheel 43 and incremental power feed mechanism, the latter 55 mechanism including, as is well known, the ratchet 44 and pawl 45 operable by the rod 46 through mechanism contained within the box 47.

The operation of the method and apparatus of the present invention is as follows: The work 60 pieces have the inner face 11 completely formed to a radius equal to the radius of the various supporting portions on the mandrel 15, and then placed on the said mandrel and secured in operative position by the clamping rings 25 and 26 65 and their clamping screws 27 and 28. This assembly is then placed in a machine tool between opposed work supporting centers whereupon the said assembly is rotated about the axis 24 and a tool fed relative thereto.

70 What is claimed is:

1. In a mechanism of the class described the combination with a bed, a grinding wheel rotatably mounted thereon, a work supporting table mounted on the bed, opposed head and tail stocks supported by the work table, a work carrying

mandrel between the head and tail stocks, said mandrel having formed thereon an arcuate face generated about an axis other than the axis of the mandrel, said arcuate face of the mandrel being adapted to receive a contragenerically formed face on a work piece, clamping means for securing the work piece to this seat, and means associated with the head stock for rotating the mandrel and work piece about the axis of the mandrel for thereby producing an arcuate surface on the work piece eccentric to the previously formed arcuate surface thereon. 5

2. In a grinding machine for producing work pieces having an arcuate face thereon generated about an axis eccentric to the axis of an arcuate 10 second face on the work piece comprising a mandrel, the axis of which is coincident with the axis of the arcuate face to be generated on the work piece, the mandrel having formed thereon an arcuate seat generated about an axis 15 eccentric to the axis of the mandrel and adapted to receive the second face on the work, clamping means for securing the work piece to the arcuate seat on the mandrel, a grinding wheel mounted on the bed, and means for effecting a 20 relative rotation between the work and grinding wheel. 25

3. In a grinding machine for producing work pieces having an arcuate face thereon generated about an axis eccentric to the axis of an arcuate 30 second face on the work piece comprising a mandrel, the axis of which is coincident with the axis of the arcuate face to be generated on the work piece, the mandrel having formed thereon an arcuate seat generated about an axis 35 eccentric to the axis of the mandrel and adapted to receive the second face on the work, clamping means for securing the work piece to the arcuate seat on the mandrel, a grinding wheel mounted on the bed, means for effecting a 40 relative rotation between the work and grinding wheel, and means for effecting a relative feed between the grinding wheel and work while said wheel and work are being rotated. 45

4. In a grinding machine for simultaneously producing a plurality of work pieces, each adapted to have an arcuate face generated thereon about an axis eccentric to a previously formed arcuate surface comprising a rotatable grinding wheel, a work supporting mandrel adjacent the grinding wheel and rotatable about the axis thereof, said mandrel having formed thereon a plurality of arcuate seats each adapted to receive the arcuate surface of the work piece, means carried by the mandrel adjacent each end of the lateral edges of each arcuate seat thereon and between which the work is disposed for accurately positioning the work relative to the mandrel, and clamping means for securing the work pieces to the mandrel. 55

5. In a grinding machine for simultaneously producing a plurality of work pieces, each adapted to have an arcuate face generated thereon about an axis eccentric to a previously formed arcuate surface comprising a rotatable grinding wheel, a work supporting mandrel adjacent the grinding wheel and rotatable about the axis thereof, said mandrel having formed thereon a plurality of arcuate seats each adapted to receive the arcuate surface of the work piece, 70 means carried by the mandrel adjacent each end of the lateral edges of each arcuate seat thereon and between which the work is disposed for accurately positioning the work relative to the mandrel, and clamping means for securing the 75

- work pieces to the mandrel, comprising a clamping screw for each end of the work for holding said ends of the work against the mandrel seats. 8. A mandrel for supporting a plurality of segmental bearing shoes while having the arcuate bearing face on the contact rib thereof formed comprising a mandrel having formed thereon a plurality of arcuate seats each generated about an independent axis eccentric to the axis of the mandrel, means carried by the mandrel circumferentially thereof and defining the lateral limits of the bearing shoe seats, said arcuate seats being coincident to the segmental shoes bearing surfaces, and means encircling the bearing shoes and mandrel for securing said shoes to the mandrel, comprising a clamping screw for each end of the shoes.
- 5 6. In a grinding machine for simultaneously producing a plurality of work pieces, each adapted to have an arcuate face generated thereon about an axis eccentric to a previously formed arcuate surface comprising a rotatable grinding wheel, a work supporting mandrel adjacent the grinding wheel and rotatable about the axis thereof, said mandrel having formed thereon a plurality of arcuate seats each adapted to receive the arcuate surface of the work piece, means carried by the mandrel adjacent each 10 end of the lateral edges of each arcuate seat thereon and between which the work is disposed for accurately positioning the work relative to the mandrel, means for securing the work pieces to the mandrel, comprising a clamping screw for each end of the work for holding said ends of the work against the mandrel seats, and a ring 15 encircling the work and mandrel through which the clamping screws are axially adjustable. 7. A mandrel for supporting a plurality of segmental bearing shoes while having the arcuate bearing face on the contact rib thereof formed comprising a mandrel having formed thereon a plurality of arcuate seats each generated about an independent axis eccentric to the axis of the mandrel, means carried by the mandrel circumferentially thereof and defining the lateral limits of the bearing shoe seats, said arcuate seats being coincident to the segmental shoes bearing surfaces, means encircling the bearing shoes and mandrel for securing said shoes to the mandrel, comprising a clamping screw for each end of the shoes, and a pair of rings, one for each end 20 25 30 of the shoes and supporting the clamping screws at said ends of the shoes.

ALBERT H. DALL.
